TOY BUILDING BLOCK

Vincent J. Esposito, Jr., Wayne Township,
Passaic County, N. J.

Application December 1, 1954, Serial No. 33,352

Term of patent 14 years

(Cl. D34—15)

FIG. 1

FIG. 3

FIG. 2

Fig. 1 is a front elevational view of a toy building block showing my new design;

Fig. 2 is a rear elevational view thereof;

Fig. 3 is a side elevational view thereof; and

Fig. 4 is a cross-sectional view thereof, taken on line 4-4 of FIG. 1.

I claim:

The ornamental design for a toy building block, as shown.
